UNITED STATES PATENT OFFICE.

JOHN W. NARRON, OF OAKLAND, CALIFORNIA, ASSIGNOR TO MECHANIC'S STATIONARY STAGE COMPANY, OF RICHMOND, CALIFORNIA, A CORPORATION OF CALIFORNIA.

PAINTER'S LADDER-SUPPORT.

1,143,058.

Specification of Letters Patent. Patented June 15, 1915.

Application filed October 19, 1912, Serial No. 726,688. Renewed November 10, 1914. Serial No. 871,401.

To all whom it may concern:

Be it known that I, JOHN W. NARRON, a citizen of the United States, residing at Oakland, in the county of Alameda and State of California, have invented new and useful Improvements in Painters' Ladder-Supports, of which the following is a specification.

The object of the present invention is to 10 provide an improved support for painter's swinging stages or falls, used in painting the outside of houses.

It has heretofore been the practice to support such stages or falls by means of hooks 15 which engage the roof of the house and extend sufficiently far over the edge of the roof to enable the stage to be suspended therefrom by means of ropes and blocks, which ropes can be extended or taken in 20 from time to time to vary the level of the stage.

One objection to this means of supporting the stage is, that since it swings loosely from the points at the top of the building, there 25 is great liability, especially when the stage is swinging from a great height, of the stage being accidentally pressed away from the side of the building by one of the painters and thus causing another painter thereon to 30 lose his balance, thereby causing the stage to swing still farther away from the building, so that both of the workmen are then thrown off. By reason of the stage being thus loosely suspended from points at the top 35 of the house and therefore being liable to swing away from the wall of the building with very little pressure, it is necessary for the painter to be very careful not to apply undue pressure to the wall of the building, 40 for this would cause the stage to swing away from said wall, with the results above referred to. Consequently the painter can only work at about two-thirds of his full speed.

45 A further objection incidental to the old form of support is that under certain conditions, as, for instance, in moving from one end of the stage to the other, the stage has to be steadied by ropes extending therefrom 50 to the ground and held by a body or another workman, and through such person's carelessness there is a possibility of the stage becoming freed from its support at one end, and of the painter being precipitated there- 55 from to the ground.

The object of the present invention is to provide a support for such stages, which will avoid the above objections, and which will hold the stage securely in the proper position for painting, which position can be readily adjusted by a painter without the necessity of employing an assistant on the ground, either to adjust the stage, or to hold it steady while being so adjusted.

A further object of my invention is to provide a device, which while attaining the above objects, can be applied equally well to all buildings having ordinary forms of eaves trough and roof.

A further object of the invention is to provide such a support for ladders, which can be used to support staging employed by painters working on high bill-boards, or the like.

In the accompanying drawing, Figure 1 75 is a plan view of the support as applied to the eaves or drain trough of a house; Fig. 2 is a side view thereof; Fig. 3 is a side view of the same as used for painting on a bill-board, or a wall extending above a flat roof 80 of a building; Fig. 4 is a broken plan view thereof; Fig. 5 is a front view and Fig. 6 a cross-sectional view of a clamp bar used 85 with the support, for penetrating the shingles of a roof; Fig. 7 is a broken detail plan view of the device.

Referring to the drawing, 1 indicates the roof of a building, having an eaves or drain trough 2.

3 indicates steel plates, through which are 90 passed the terminal portions of tubes 4, each of which is bent in the form of a yoke. Said tubes are passed, not only through said plates, but also through a wooden bar 5, and also through plates 6, said plates 3 and 6 95 lying against inner and outer sides respectively of the terminal portions of the bar. Said tubes are secured to said plates and bar by means of nuts 7, 8, screwed on said tubes, on the opposite sides of said bar, and thus 100 clamping the bar and plates together.

9 indicates short sleeves, around the outer side members of the yokes, which can be moved longitudinally on said tubes, and secured by set screws 11 to adjust the device 105 to any desired position according to the width of the trough with which it is to be used. Through lugs 12 extending from the inner side of the sleeves 9, are screwed vertical adjusting screws 13, the lower ends of 110

which engage the upper surfaces of clamps 14, which are pivoted, as shown at 16, to the under sides of said sleeves. Said upper surfaces are so formed in relation to the adjusting screws 13, that in the clamping position the lower ends of the screws 13 are substantially on the same level as the pivots 16. The set screws 11 extend horizontally and do not interfere with the operation of the screws 13. The upper portions of the clamps 14 are hollow, and of triangular cross-section, and connecting the two clamps of each support is a bar 17 of wood, extending the full length of the support, the ends of which are driven firmly in said hollow clamps. A bar 18 of wood, triangular in cross-section, is secured at its ends to the lower portions of the two plates 3. The lower portions of said plates 3 and clamps 14 extend obliquely downward, and at their extreme lower edges they are formed with outwardly extending dogs 19, 21, which engage the inner surfaces of opposite sides of the trough. Through the oblique portions of the plates 3 are passed screws 22 which are screwed through, and out of, the terminal portions of the bar 18, their pointed ends engaging the inner side of the eaves-trough. To the upper side of said bar 18 are secured upwardly extending brads 20 which can engage the under surface of the outermost shingles to additionally secure said support.

In the ends of the inner side members of the yokes, are inserted pointed rods 23, secured in any desired position in the tubes 4, by means of set screws 24, screwed through the inner nuts 7, on said tubes and bearing down upon said rods. However, said rods 40 may otherwise be secured adjustably by forming them with threads and screwing them in the ends of said tubes, also threaded.

As an additional means of securely holding the support in the desired position in relation to the roof of a house, there are secured against the terminal portions of the bar 5, by means of the nuts 8, plates 6, the ends of which are formed with vertical grooves 27, 28. In said grooves can slide vertically lugs 29, 31, extending upwardly from a clamp bar 32, which clamp bar, as clearly shown in Fig. 6, can be raised or lowered by means of screws 33, the lower ends of which pass through lugs 34, extending from the rear side of said clamp bar, said screws being screwed through lugs 36, extending from the front side of said plates. On the under side of said clamp bar are secured prongs or spikes 37, which can be firmly driven into the shingles 38 of the roof.

41 indicates a rectangular frame, having tubular ends 42 slidable upon the inner members of the yokes, and having one fixed longitudinal member 43 and one movable lon-

gitudinal member 44, pivoted at 46 upon an end member. This frame can be adjusted to any desired position upon the yokes and then clamped in said position by means of set screws 47.

The following is the manner in which the device is ordinarily used when supported on a house. The painter first sets his ladder 48 against the roof of the building, and ascends the ladder, carrying with him the support. If the ladder does not extend a considerable height above the roof of the building, then he passes the support over the ladder and into such a position that the ladder extends upwardly within the frame 41 on said support, said frame being at this time in its innermost position, near the roof of the building. The painter then secures the support to the building by pressing the prongs 37 into the roof and by screwing down the screws 13 so that the clamps 14 engage the eaves-trough. When this support is sufficiently secured, the painter then, by pressing with his foot against the wall of the building, moves the frame and ladder away from the building, into a position in which the ladder when properly adjusted will stand vertical therein and at a suitable distance from the wall of the building to support a scaffold thereon. In general the ladder will not be vertical when the frame has been moved to this distance, but it will be necessary to move the bottom of the ladder in toward the wall of the building so that the ladder stands vertically in the frame. When the frame has been moved to a proper position, it is then secured upon the support by screwing down the set screws 47. Should the ladder extend so far above the roof of the building, that it is not practical to pass the frame over the ladder, then the outer movable side 44 of the frame is moved outward to permit the frame to be moved to a proper position around the ladder, and the movable side 44 is brought again to its proper position in parallelism with the fixed side, and a nut 49 on the threaded end 51 of said movable side 44 is then screwed on to a threaded fixed extension 52 from the adjacent end of the frame. The frame is provided with longitudinal extensions 54, which are used when it is desired to support the ladder to a position in a vertical plane at right angles to that shown in Fig. 2, that is, at right angles to the wall of the building, or for any other desired purpose. These extensions 54 when moved to the proper distance from the wall of the building, are also useful for supporting scaffold poles.

The support may also be secured to the roof of a house without an eaves-trough, by nailing thereon short cleats, and causing the dogs 19 to engage the upper ends of said cleats, while the pointed ends of the rods 23

engage the butt ends of the shingles made additionally secure by nailing, or engage an upper cleat secured in like manner.

Figs. 3 and 4 illustrate the arrangement of the parts of the support when attached to a high bill-board 58 or a wall extending above the flat roof of a house. When so using the support, both the plates 3 and the clamps 14 are reversed, so that their dogs 10 19, 21, extend inward or toward one another, and, as will be seen, these dogs then engage opposite sides of the bill-board, while the brads 22 engage the under side of the top framing 57 of the bill-board. The 15 bar 32 is not now used. In other respects the mode of operation is similar to that before described.

The device is absolutely safe if properly used for it will be observed that the support 20 bears only its own weight, and no part of the weight of the ladder or scaffold. Even if the support should break, the only result would be that the ladder would fall against the building, the weight of the scaffold being 25 on the inside.

I claim:—

1. In combination with the eaves trough of a house, a supporting device removably secured to the eaves trough, means for supporting, against lateral displacement from such device, a ladder on the ground, and means for securing said supporting means on said supporting device at different points thereon.

35 2. In combination with the eaves trough of a house, a support removably secured to said eaves trough, and a ladder-supporting frame secured to, and wholly supported by, said support, and adjustable, independently 40 of said support, to and from said eaves trough.

3. In combination with the eaves trough of a house, a support having parts adapted to engage the inner surface of the eaves 45 trough, means for separating said parts from each other to cause them to engage said surface at different points, and a ladder-supporting frame movably secured to said support.

50 4. In combination with the eaves trough of a house, a support comprising two yokes, devices supported upon the outer members of said yoke and adapted to engage the eaves trough to secure the support thereon, and a 55 ladder-supporting frame movably secured to the inner members of said yokes.

5. In combination with the eaves trough of a house, a support containing two tubular yokes, devices supported upon the outer members of said yokes and adapted to engage 60 the eaves trough to secure the support thereon, a ladder-supporting frame movably secured to the inner members of said yokes, and rods secured in the ends of said yokes and having sharpened ends adapted to 65 engage the roof of the house.

6. In combination with the eaves trough of a house, a support having two pairs of parts adapted to engage the two sides of the inner surface of the eaves trough, means for 70 separating said parts from each other to cause them to engage said surface, means for connecting corresponding parts of each pair, and a ladder-supporting frame movably secured to said support.

7. In combination with the eaves trough of a house, a support comprising two yokes, devices supported upon the outer members of said yoke and adapted to engage the eaves trough to secure the support thereon, and a 80 ladder-supporting frame movably secured to the inner surface of said yokes and having outwardly extending arms.

8. In combination, a ladder-supporting frame, a support upon which said frame is 85 adjustably secured, two pairs of clamps carried by said supports, the clamps of each pair being adapted to engage opposing surfaces of the structure with which the device is to be used, means for moving one of said 90 clamps relatively to the other to cause them to engage said surfaces, and means for connecting corresponding clamps of each pair.

9. In combination, a ladder-supporting frame, having outwardly extending arms, a 95 support upon which said frame is adjustably secured, two pairs of clamps carried by said supports, the clamps of each pair being adapted to engage opposing surfaces of the structure with which the device is to be 100 used, means for moving one of said clamps relatively to the other to cause them to engage said surfaces, and means for connecting corresponding clamps of each pair.

In testimony whereof I have hereunto set 105 my hand in the presence of two subscribing witnesses:

JOHN W. NARRON.
